COMBINATION COSTUMER AND CLOTHES
HAMPER

Donald H. Hansen, Oconto Falls, and George L. Hauan,
Two Rivers, Wis.

Application June 18, 1957, Serial No. 46,631

Term of patent 14 years

(Cl. D58—4)

Fig. 1.

Fig. 2.

Fig. 3.

Fig. 4.

Figure 1 is a side elevational view of a combination costumer and clothes hamper, showing our new design, Figure 2 is a front elevational view thereof, Figure 3 is a rear elevational view thereof, and Figure 4 is a top plan view thereof.

The side not shown is the same as the side shown. We claim:

The ornamental design for a combination costumer and clothes hamper, as shown and described.
